WILLY ZELETZKI, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

KEY CIRCUIT FOR TUBE SENDERS.

Application filed March 26, 1923, Serial No. 627,576, and in Germany April 19, 1922.

The usual method of controlling the grid of a tube generator circuit by means of a key consists in interrupting the grid conductor, i. e. the high frequency path and the 5 path through which the grid direct current is discharged in rhythm with the operation of the key. As is well known, it is also possible to leave the high frequency path undisturbed and to control by means of the key 10 only the direct current discharge path of the grid.

The latter is usually accomplished by providing a condenser in the grid conductor, and by further providing a direct current 15 path which is arranged in parallel with the condenser, and which may be opened and closed by the key. In order to protect the key sending apparatus against high frequencies, it is usually connected in series 20 with high frequency choke coils. With this arrangement when the key is closed, the high frequency current flows through the condenser, and the grid direct current flows through the choke coils and the key.

25 The condenser has heretofore been so proportioned that the drop of high frequency potential is very slight. In order to accomplish this, the condenser may be relatively small (a few thousand cm.) because the high 30 frequency current flowing therethrough is very small. When the grid circuit is interrupted by the key, the oscillations generated by the tube in the oscillating circuit will cease but the normal current will continue 35 to flow through the tube, due to which, under certain circumstances, even larger losses may be caused in the tube than during the oscillating condition. This is particularly the case when the direct current potential in the plate circuit of a tube is materially increased upon the interruption of the 40 grid circuit by the key so that the plate current tends to be much higher in the normal condition than it would be if the voltage of 45 the plate current source did not increase with decrease in current drain.

For the purpose of eliminating or reducing as far as possible the normal current flowing through the tube during the resting 50 condition, it has been suggested to provide a separate source of current which upon the opening of the key applies a negative potential to the grid of the tube. However, the

circuit arrangement proposed for this purpose is complicated because a separate source of current is necessary and a separate switching contact must be provided for this current source.

Experiments conducted in accordance with the present invention have shown that by increasing the condenser which is connected in parallel with the key out of proportion, often 50 or 100 times or more, with the size necessary to maintain the drop of the high frequency potential in the grid circuit at the slight degree required, the normal current flowing through the tube may be so reduced as to be approximately equal to zero without the provision of a separate battery. The same result may be attained by a combination consisting of a very high resistance 70 in parallel with the condenser.

In the drawing,

Fig. 1 is a diagrammatic representation 75 of a circuit arrangement embodying the invention; and

Fig. 2 is a diagrammatic representation of a modified form of the invention.

The illustrated construction comprises a three-electrode vacuum tube 2 having a grid 80 4 and a grid-filament circuit 6. Arranged in series in the grid-filament circuit are a key 8 and a choke-coil 10, and connected in parallel with the key 8 and the choke-coil 10 is a condenser 12 of a capacity many times, 85 for example, 50 or 100 times, larger than that required to maintain the drop of high frequency potential in the grid-filament circuit at the required small degree.

As shown in Fig. 2, a very high resistance 90 14 is arranged in parallel with the condenser 12 for the purpose of preventing losses in the tube while the key is open by reducing the current in the tube at such times approximately to zero.

Having described my invention, what I claim is:

A circuit arrangement for tube generators comprising a three-electrode vacuum tube, a grid-filament circuit for said tube, a key and a choke coil arranged in series in the grid-filament circuit, a condenser connected in parallel with the key and choke coil, and a high resistance connected in parallel with the condenser.
